UNITED STATES PATENT OFFICE.

CHARLES R. NELSON, OF PORTLAND, MAINE.

DESIGN FOR A RADIATOR.

SPECIFICATION forming part of Design No. 19,739, dated April 1, 1890.

Application filed February 5, 1890. Serial No. 339,348. Term of patent 14 years.

To all whom it may concern:

Be it known that I, CHARLES R. NELSON, a citizen of the United States, residing at Portland, in the county of Cumberland and State of Maine, have invented certain new and useful Improvements in Designs for Radiators; and I do hereby declare the following to be a full, clear, and exact description of the invention, such as will enable others skilled in the art to which it appertains to make and use the same.

My invention relates to a new and useful design for steam or hot-water radiators, and in the accompanying photograph is represented a radiator which embodies the essential features of my design.

In the photograph, A represents the main portion of the radiator, which is composed of a row of vertical pipes surmounted by an or-

namental top B. Projecting forward from the lower portion of the radiator is a base or foot-rest C, surmounted by an ornamental grating e, and this foot-rest is also surmounted by a rail D. The particular form of grating which I show for the top of the radiator and the base, and the particular rail here shown, I do not wish to limit myself to, as it is the general configuration of the radiator which renders it pleasing to the eye and which I desire to cover.

I claim—

The design for radiators, substantially as herein described and shown.

In testimony whereof I affix my signature in presence of two witnesses.

CHARLES R. NELSON.
